CLAIM

The ornamental design for a data card, as shown and described.

DESCRIPTION

FIG. 1 is a front perspective view of a first embodiment of a data card;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a second embodiment of the data card; and,

FIG. 9 is a front view thereof.

The undisclosed surfaces of the second embodiment are not shown because they form no part of the design claim. The even dash broken lines are included for illustrative purposes only and form no part of the design claim. The dot-dash broken lines depict the boundary between the claimed portions of the design and the unclaimed portions.

The Applicant reserves the right to: 1) convert some or all of the broken lines to solid lines; and/or 2) convert selected solid lines to broken lines during the course of prosecution and/or in one or more continuation applications, since the figures convey that the inventors had possession of the solid line features and the broken line features as of the date of filing.
